(57) **CLAIM**

The ornamental design for a garment, as shown and described.

DESCRIPTION

FIG. 1 is a front view of a garment according to a first embodiment of the design;

FIG. 2 is a rear view thereof;

FIG. 3 is a right side view thereof;

FIG. 4 is a left side view thereof;

FIG. 5 is a front perspective view thereof;

FIG. 6 is a rear perspective view thereof;

FIG. 7 is a front view thereof shown in an environment of use;

FIG. 8 is a front view of a garment according to a second embodiment of the design;

FIG. 9 is a rear view thereof;

FIG. 10 is a right side view thereof;

FIG. 11 is a left side view thereof;

FIG. 12 is a front perspective view thereof;

FIG. 13 is a rear perspective view thereof; and,

FIG. 14 is a front view thereof shown in an environment of use.

The portions of the garment shown in broken lines in FIGS. 1-14 do not form part of the claimed design. The broken line showing of the feet, arms, and torso in FIGS. 7 and 14 is for the purpose of illustrating portions of the environmental structure and forms no part of the claimed design. The solid lines shown in FIGS. 1-14 illustrate the claimed design and also illustrate the boundary of the claimed design, that is, the portions of the surface of the garment adjacent to the solid lines do not form part of the claimed design.
